JOSEPH WHITE, OF PISCATAWAY TOWNSHIP, NEW JERSEY, ASSIGNOR TO HALL PRINTING PRESS COMPANY, OF DUNELLEN, NEW JERSEY, A CORPORATION OF NEW JERSEY.

SHEET REGISTERING AND GAGING MECHANISM.

1,367,110.

Specification of Letters Patent.

Patented Feb. 1, 1921.

Application filed August 7, 1912. Serial No. 713,744.

To all whom it may concern:

Be it known that I, JOSEPH WHITE, a citizen of the United States, residing at Piscataway township, State of New Jersey, (post office address, Bound Brook, New Jersey), have invented certain new and useful Improvements in Sheet Registering and Gaging Mechanism; and I do declare the following to be a full, true, and exact description of said invention, such as will enable others skilled in the art to which it appertains to make use of the same.

This invention relates to mechanism for positioning sheets in machines for operating on such sheets and particularly to devices for positioning sheets so that they will be printed in accurate register in printing machines. The devices which I have illustrated are intended to position the sheet longitudinally only, devices for positioning it laterally being no part of my present invention, and therefore, not shown. My novel mechanism may be used in connection with any form of sheet handling devices by which sheets are presented to machines.

In my present invention, I have provided means by which sheets may be presented to a sheet carrier with very great accuracy and by simple and efficient mechanism, the carrier being either a part of the machine for operating on the sheet or a device which may be readily attached to such machine. My novel devices include not only mechanism for accurately positioning the sheets against a gage, but also devices by which such gages may be readily adjusted and particularly while the machine is in motion.

In the drawings, Figure 1 represents a side elevation of a rotary machine in a more or less diagrammatic form, this machine being one which I have chosen for purposes of illustration to show the application of my novel devices.

Fig. 2 is a side elevation of a portion of my novel mechanism, some of the parts being broken away.

Fig. 3 represents a partial end elevation of the mechanism of Fig. 2, looking in the direction of the arrow 3 in Fig. 2.

Fig. 4 is an enlarged perspective view of a portion of my novel mechanism, showing particularly the devices for supporting and moving the gage, the sheet wiper and the sheet guides.

The corresponding parts are referred to

both in the drawings and the following description by similar reference characters.

Referring now to Fig. 1, 9 represents the impression cylinder and 10 the form cylinder of the printing machine which I have chosen for purposes of illustration. The machine is provided with the usual inking arrangement and a delivery mechanism below the impression cylinder 9. This inking and delivery mechanism being no part of my present invention, no detailed description thereof is necessary. 11 is a feed cylinder carrying a set of grippers 12 mounted on a shaft 13 and operated by a cam lever and roller running on a cam 14, all in the usual manner. These grippers 12 are shown at the feeding point of the cylinder 11, and it will be understood that they close on a sheet presented at this feeding point and carry it to the impression cylinder 9 to be taken by the usual set of sheet grippers on that cylinder. The grippers 12 strike against abutments 15 carried by the shaft 16 mounted in the cylinder 11. 17 represents sheet supports extending substantially tangent to the cylinder 11 at the feeding point thereof, these supports being mounted on brackets 18 attached to a fixed shaft 19 held in the side frames of the machine. 20 represents a series of tape pulleys mounted on the shaft 21, running in the side frames of the machine. It will be understood that the tapes 20' carried by the pulleys 20 lead from a source of supply for the sheets, usually a sheet separating device by which sheets are taken one by one from a pile, and that any other suitable form of sheet support and forwarding device may be used. 22 represents a roller mounted on an arm 23 attached to a shaft 24 free to rotate in the side frames of the machine. The roller 22 is held in contact with the pulleys 20 by the action of a cam 25 acting through a cam lever 26, link 27 and lever 28, the latter being fastened to the shaft 24. The roller 22 is held away from the pulley 20 by the spring 29 acting on the shaft 24, as shown particularly in Figs. 1 and 2. It will be understood that as many of the rollers 22 as are necessary will be provided on the shaft 24.

30 is a shaft extending across the machine and free to rotate in the side frames thereof and carrying one or more sheet wipers 31 attached thereto. This wiper may be of any suitable material, though preferably of 110

rubber, and while for most purposes, it could be a roller having either a whole circumference or a circumference partly cut away, I prefer to make it in the form 5 shown, since, as will be apparent, the small active portion of the wiper which I have shown is sufficient. The shaft 30 has attached to it a gear 32 meshing with a gear 33 on the shaft of the feed cylinder 11, this 10 gear being larger than the circumference of the feed cylinder 11 and the gear 32 being smaller than the circle generated by the end of the wiper 31. This arrangement causes the active end of the wiper 31 to travel at a 15 considerable faster speed than the periphery of the cylinder 11.

34 is a gear loosely mounted on the shaft 19 and meshing with gears 32 and 35, the latter being attached to the shaft 21. This 20 gear 35, in the device illustrated, is larger than the pulleys 20 in approximately the same ratio that the gear 33 is larger than the cylinder 11, so that the pulleys 20 and the cylinder 11 have substantially the same 25 surface speed.

As will be seen from an inspection of Fig. 2, the supports 17 are mounted so as to lead a sheet from the tapes passing around the pulleys 20 to the feeding point of the cylinder 11.

36 is a sheet front gage of which one or more may be provided. Each of these gages is adjustably mounted on the end of an arm 37 and held against vertical movement by a 35 screw 36'. The arm 37 is loosely mounted on the shaft 38 of the cylinder 11. 39 is an arm attached to the shaft 38 directly behind the arm 37. Between the arms 37 and 39 is a wedge 40, with which the faces of 40 arms 37 and 39 are arranged to coöperate. As shown particularly in Fig. 3, a link 41, surrounded by a spring 40' and provided with a stop pin 72, connects the wedge 40 with a lever 42 pivotally mounted on a 45 bracket 43 attached to the cylinder 11. This lever 42 carries a ball or roller 44, which is arranged to contact with the face of a cam 45 mounted on a rod 46 in the side frame of the machine. The cam 45 is also provided 50 with a steady pin 47 engaging with the side frame. The end of the rod 46, outside of the side frame, is screw-threaded and mounted thereon is a nut 48 provided with worm teeth. These teeth engage with a 55 worm gear 49 attached to a shaft 50 mounted in brackets on the side frame and extending longitudinally thereof, as shown particularly in Fig. 1. It will be understood that if the gage 36 is duplicated on the opposite side of the machine, as will usually be the case, the mechanism just described will also be duplicated on that side of the machine, and such duplication is shown in Fig. 1, in which the shaft 50 is shown extending to a point adjacent the delivery pile

of the machine. On this side of the machine, the shaft 50 is broken at 51, where a universal joint is provided and the bracket 52 is slotted to permit vertical motion to the outer end of the shaft 50, such vertical motion being prevented normally by the spring 53. The outer end of the shaft 50 is provided with a hand wheel 54 and spiral gear 55 meshing with a spiral gear 56 mounted on a shaft 57 extending across the 75 machine and having mounted on its opposite end, a spiral gear similar to 56, which in turn meshes with a spiral gear similar to gear 55 on the end of the shaft 50 on that side of the machine. The shaft 57, on the 80 side of the machine shown in Fig. 1, will preferably be provided with a hand wheel 58, similar to hand wheel 54.

As a means by which the operator may readily determine the location of the gages 85 36, I provide a suitable indexing device for the shaft 50 which may be of any convenient type and located in any convenient place. As one form of such device, I have shown in Fig. 1 on the shaft 50, a worm wheel 73 90 which is engaged by a roller on the end of lever 74, pivoted on the side frame of the machine, the opposite end of the lever passing over the index 75. It is obvious that the position of the lever 74 in reference to the 95 index 75 will indicate at any time the position of the gage on that side of the machine. The shaft 50 on the opposite side of the machine would be provided with a similar indexing device. These indexing devices 100 may also be placed adjacent the hand wheels 54 and 58 in any convenient manner.

In the form of device illustrated, the gage 36 is mounted on a member 59, which is held adjustable to the arm 37 by a screw 37', the 105 gage 36 being vertically adjustable on the member 59, as shown particularly in Fig. 4, and held by the screw 36'. The member 59 has an extension 61 projecting over the inner end of the gage 36, also as shown particularly in Fig. 4. The member 59 has another projection 60, which has a face lying in the periphery of the cylinder 11. This member 60 constitutes an abutment with which the wiper 31 coöperates, for a purpose 110 explained hereafter.

In addition to the regular sheet grippers 12, the shaft 13 is provided with one or more sets of guiding fingers 62 loosely mounted on shaft 13 in a manner more particularly illustrated in Fig. 4. 65 represents a member attached to the shaft 13 and adjacent to a projection 66 on the guide 62. A spring 67 is interposed between the member 65 and the projection 66 and a member 68 forming part 125 of the member 65 is provided to limit the motion of the end 66 of the guides 62. The guides 62 are preferably arranged to contact with the gage 36 and to extend beyond said gage adjacent the member 60, as shown part 130

ticularly in Fig. 4, and preferably two of these guides are provided on either side of the path of operation of the wiper 31.

69 is an arm connected to the hub of the arm 37 and carrying a rod 70 surrounded by a spring 71, the latter abutting against the arm 39.

The operation of my novel sheet positioning device is as follows: The cylinders 9, 10 and 11 and the connected mechanism being in motion, a sheet is carried by the tapes 20 beneath the rollers 22, which at this time are in contact with the pulleys 20. The sheet is forwarded by the contact between the pulleys 20 and the rollers 22 along the supports 17 to the feeding point of the cylinder 11. As the grippers 12 approach this feeding point, they will have been opened by the cam 14 in the usual manner and the gage 36 will be considerably removed from the gripper abutments 15 by reason of the fact that the wedge 40 would have been withdrawn from between the arms 37 and 39 by the spring 40', thus permitting the spring 71 to move the arm 37 in relation to the cylinder, toward the right of Fig. 2. As the gage 36 is carried toward the feeding point, the roller 44 will engage the cam 45 to thrust the wedge 40 between the arms 37 and 39, thus giving a motion to the gage 36 clockwise of the view in Fig. 2, or in a direction the reverse of the motion of the periphery of cylinder 11. The amount of this motion will obviously be controlled by the amount of motion given the roller 44 by the cam 45. This reverse motion of the gage 36 occurs at the time when the head of the sheet reaches the feeding point and comes into engagement with the wiper 31 and the wiper abutment 60. About the same time that the wiper 31 engages the sheet, the roller 22 is lifted therefrom to permit the wiper to draw the sheet forward at a greatly increased speed.

45 Just prior to the engagement of the sheet by the wiper 31, the shaft 13 will have been turned so as to bring the grippers 12 and the guides 62 down close to the gripper abutments 15, the members 60 and the gage 36. 50 Because of the arrangement shown particularly in Fig. 4, the guides 62 precede the fingers 12 and engage with the top of the gage 36 before the grippers 12 close on the sheet. An inspection of Figs. 2 and 4 will 55 show that, in the preferred form, the members 60 and the abutments 15, on the one side, and the guides 62, on the other side, form a sheet guideway leading to the gage 36 and that the wiper 31 operates on the 60 sheet held in this guideway. After the sheet has been pushed by the wiper 31 against the gage 36, the fingers 12 close thereon by reason of the further rotation of the shaft 13, this further rotation being permitted by the 65 yielding of the spring 67. The sheet now

being engaged between the grippers 12 and the gripper abutment, the wiper 31 passes out of contact with the sheet and the guide 36 will be moved away from the front edge thereof by the further travel of the cylinder 70 11 carrying the roller 44 along the cam 45. When the grippers 12 open to transfer the sheet from the cylinder 11 to the cylinder 9, the guide 62 will be moved out of the way by the rotation of the shaft 13 and the contact 75 of the members 66 and 68. In the arrangement shown, the wiper 31 will contact with the sheet more than once after positioning it against the gage 36 but since the cylinder 11 is provided with a wiper abutment only at a 80 point adjacent the gage 36, the sheet will not be disturbed by these additional contacts.

From the description just given, it will be seen that with my novel device, sheets may be presented to a carrier at a speed approximately that of the carrier and with the head of the sheet very accurately positioned against a gage carried by said carrier, since this edge is held so that it cannot move up or down the gage when brought in contact 85 therewith, this motion up and down having heretofore been one of the chief sources of error in positioning sheets. It will also be seen that at the instant in which the gaging takes place, the relative velocities of the sheet 90 and gage may be very high, so that a sheet considerably out of square may be brought accurately in position against both gages in the small fraction of time in which the sheet is being presented to the gage. This high 95 relative speed is accomplished by the motion of the gage 36 in a direction contrary to that of the sheet under the control of the wiper 31.

By reason of the vertical adjustment of the gage 36 and the use of these gages as 100 stops for the guides 62, I am able to provide a space between the member 60 and the guides 62 which will be proportioned to the thickness of the sheet to be gaged. This 105 adjustment is materially assisted by the extension member 61 of the member 59, for it is possible to place a sheet of the paper or other material to be gaged between this extension 61 and the gage 36 before fastening the gage 36 in position by the screw 36' and thus fixing the space between the guides 62 and the member 60 according to the thickness 110 of the sheet to be gaged.

While I have shown the member 60 as mounted on the arm 37 and therefore having 115 a speed less than that of the periphery of the cylinder 11 at the time the wiper 31 cooperates therewith, it is obviously possible to mount this member 60 on an arm independent of the arm 37, in which case it may 120 have the same speed as the periphery of the cylinder or by the addition of suitable mechanism, may have even a greater speed at the time the wiper 31 is acting.

While I have shown the guides 62 as op- 130

erated by the shaft 13, it is obviously possible that these guides may be operated in any other suitable manner and that they may be mounted on a shaft entirely independent of 5 the gripper shaft. The arrangement I have shown, however, is extremely simple and convenient. It is also possible to use the grippers 12 as the overguides in place of the guides 62. This can be accomplished readily 10 by shaping the cam 14 so that the grippers 12 will be closed to the position of the guides 62 shown in Fig. 2 when the parts have arrived at the position shown in that figure and holding them in this position until their 15 guiding function has been accomplished and then closing them on the sheet. Even when the overguides 62 are used, the grippers 12 assist in positioning the sheet, for it is obvious that the edge of the sheet between the 20 sets of guides 62 will be held up in place by the grippers 12 before the latter close on it. It will also be obvious that the guides 62 co-operate with the gripper abutments 15 as well as with the members 60, in the sense that 25 such abutments are on one side of the sheet and the guides 60 on the other, and so form a sheet guideway between them, even though the abutments 15 and the guides 60 may not be in the same radial lines on the cylinder 11.

30 It is also obvious that many different forms of mechanism for operating the arm 37 may be provided and that the arm 37 may be replaced by any movable support for the gage 36. I find the arrangement of the arm 37 35 turning around the same center as the cylinder 11 particularly useful, since then the motion of the gage 36 is entirely in the path of the periphery of the cylinder 11. For some purposes, it will be found useful to 40 adapt the mechanism for moving the arm 37 so that the gage 36 will practically stand still in space while the sheet is being positioned against it. With the gage thus standing still and the arm 37 turning on the center 45 of the cylinder 11, the face of the gage remains in exactly the same position with relation to the sheet supports 17 and the periphery of cylinder 11, precisely as if the gage were supported externally of the cylinder 11.

50 While I have shown and described my feed cylinder 11 as one composed of rings, it is obvious that it may be of any type and in the use of the word "cylinder," I do not wish to be limited to the particular form shown.

It is also obvious that my device may be applied to any other form of sheet carrier, such as a pair of traveling chains or belts.

55 It is also possible to dispense with the use 60 of the wiper 31, in which case the sheet will be carried by the rollers 22 and pulleys 20 up to the feeding point at the same speed as the surface of the cylinder 11. The backward motion of the gages 36 will then produce a relative motion between the gage and

the sheet to square the sheet and to register it. While I have shown and described a separate abutment member 60 with which the grippers 12 co-operate, it should be understood that if the cylinder 11 is one having a solid surface, such as an impression surface, no separate members would be necessary, the front end of the solid surface then acting as the abutments for the wiper 31 and the grippers 12, and being the equivalent of the abutments 15 and 60.

70 While I have shown, as my preferred form, the pulleys 20 geared to move the sheet at substantially the same speed as the periphery of the cylinder 11, I do not wish to be confined to this ratio, as it is obvious that, for many purposes, the pulleys may be geared to advance the sheet faster, or even slower, than the periphery of the cylinder, and good register could be obtained, so long as there is a relative motion between the edge of the sheet and the gages 36 toward each other.

75 The mechanism which I have shown provides a simple device for altering the amount 80 of margin on the sheet or of shifting the gages to bring the sheets into register from a point remote from the feeding point and while the machine is in motion. An inspection of Fig. 3 will show that the rotation of 85 the shaft 50 will move the cam 45 toward and away from the side frame of the machine, according to the direction in which it is turned. With the parts in the position 90 shown in Fig. 3, it is obvious that the wedge 40 will have the motion produced by the travel of the roller 44 from the lowest to the highest portion of the cam 45. If the shaft 50 is turned so as to draw the cam 45 toward the side frame, the amount of motion 95 will be determined by the travel of the roller 44 from the position shown in Fig. 3, where it is held by the stop pin 72, to the highest point of the cam, which will then be much nearer the side frame than is shown in Fig. 100 3. Consequently, the gage 36, controlled by the cam 45, will be moved a less distance toward the sheet or to the left in Fig. 2, than it would be when the cam 45 is in the position 105 shown in Fig. 3, thus altering the margin 110 of the sheet. The position of the cam 45, therefore, in relation to the side frame, determines the amount of margin which the sheet will have, the gage 36 being normally 115 out of gaging position and being moved into gaging position by the mechanism of Fig. 3. Since the shaft 50 and the mechanism for controlling it is duplicated on the opposite side of the machine, and these duplicate mechanisms are connected by the shaft 57, it 120 is obvious that the turning of the wheel 54 will serve to move both of the gages 36 in the same direction and by equal amounts. If it is desired to shift one of the gages 125 without shifting the other, the wheel 54 is 130

pushed downward, thus disengaging the gears 55 and 56 and then the wheel 58 or the wheel 54 is turned, each wheel then controlling one of the gages independently of the 5 other.

It will be understood that all of the parts of my novel sheet positioning device are adjustable crosswise of the machine to bring the various gages and rollers into correct 10 relation with a sheet of any width. It will also be understood that while I have shown specific arrangements for carrying out various features of my invention, I do not wish to be restricted to these forms nor to the 15 combinations of the various features of my invention which I have disclosed, since many of these features may be used separately and in various kinds of machines.

Having now described my invention what 20 I claim as new and desire to secure by Letters Patent is as follows:

1. A sheet carrier, a sheet front gage movably mounted thereon, means to move said gage in a direction the reverse of that 25 of said carrier and while said carrier is in motion and means, operable while said carrier is in motion, to control the amount of motion of said gage.

2. A sheet carrier, a plurality of sheet 30 front gages movably mounted thereon and means to shift the gaging position of one of said gages while said carrier is in motion independently of the gaging position of the remaining gage, and an index for 35 each gage to indicate the position thereof.

3. A sheet carrier, a plurality of sheet front gages movably mounted thereon and means to shift the gaging position of one of 40 said gages while said carrier is in motion and independently of the gaging position of the remaining gage.

4. A sheet carrier having sheet taking means thereon, a sheet front gage on said carrier, means to move a sheet toward the 45 taking point of said sheet taking means at a speed substantially that of said sheet carrier and means adjacent the taking point, arranged to engage the sheet as it is moving toward said carrier, to move the sheet 50 against said gage at a speed greater than that of said carrier.

5. A sheet carrier having sheet taking means thereon, a sheet front gage on said carrier, means to move a sheet toward the 55 taking point of said sheet taking means at a speed substantially that of said sheet carrier, and means adjacent the taking point, arranged to engage the sheet as it is moving toward said carrier, moving at a speed 60 greater than the sheet and arranged to move the sheet against said gage.

6. A sheet carrier having sheet taking means thereon, a sheet front gage on said carrier, means to move a sheet toward the 65 taking point of said sheet taking means at

a speed substantially that of said sheet carrier, means to suspend the operation of said sheet moving means and means adjacent the taking point, constructed and arranged to engage the sheet at approximately the time 70 of said suspension and while the sheet is in motion and to move it against said gage at a speed greater than that of said carrier.

7. A sheet carrier having sheet taking means thereon, a sheet front gage on said 75 carrier, means to move a sheet toward the taking point of said sheet taking means at a speed substantially that of said sheet carrier, means to suspend the operation of said sheet moving means and means adjacent the 80 taking point and moving at a speed greater than the sheet and arranged to engage the sheet at approximately the time of said suspension and while the sheet is in motion and to move it against said gage.

8. A rotatable cylinder, an arm pivotally mounted on the center of said cylinder, a sheet gage mounted on said arm so as to lie substantially in the periphery of said cylinder and means to move said arm relatively 90 to said cylinder while said cylinder is rotating.

9. A movable sheet carrier, a sheet gage thereon, arranged to be moved in and parallel with the sheet carrying plane of said 95 carrier so as to maintain a fixed relation therewith throughout the movement, means to move said gage while said carrier is in motion and in a direction opposite to that of said carrier and means to support and 100 present a sheet to said carrier and said gage.

10. A cylinder, an arm loosely mounted on said cylinder, and having a sheet gage thereon, mechanism constructed and arranged to move said arm relatively to said 105 cylinder, and means to control the extent of such movement.

11. A rotatable cylinder, an arm pivotally mounted on said cylinder and having a sheet gage thereon, mechanism constructed 110 and arranged to move said arm relatively to said cylinder, means operable while said cylinder is in motion to control the extent of such movement.

12. A rotatable cylinder, an arm pivotally mounted on said cylinder and having a sheet gage thereon, a wedge between said arm and a portion of said cylinder and a cam, independent of said cylinder, constructed and arranged to move said wedge 120 as said cylinder rotates.

13. A rotatable cylinder, an arm pivotally mounted on said cylinder and having a sheet gage thereon, a wedge between said arm and a portion of said cylinder, a cam, independent of said cylinder, constructed and arranged to move said wedge as said cylinder rotates and means to move said cam to control the amount of motion of said wedge.

14. A rotatable cylinder, an arm having 130

- a sheet gage thereon and loosely mounted on said cylinder mechanism constructed and arranged to move said arm relatively to said cylinder, a movably mounted cam, independent of said cylinder, constructed and arranged to coöperate with said mechanism to shift said gage as said cylinder rotates and means to move said cam to control the extent of movement of said gage.
- 10 15. A sheet carrier, a sheet wiper adjacent thereto and independent thereof, constructed and arranged to move at a speed greater than the speed of said carrier, a sheet gage adapted to position a sheet relatively to said carrier and means to move a sheet toward said gage, said wiper being arranged to engage the sheet while it is in motion and move it toward said gage and in the direction of travel of said carrier.
- 15 20. 16. A sheet carrier, a continuously rotating sheet wiper adjacent thereto and independent thereof, constructed and arranged to move at a speed greater than the speed of said carrier, a sheet gage adapted to position a sheet relatively to said carrier and means to move a sheet toward said gage, said wiper being arranged to engage the sheet while it is in motion and move it toward said gage and in the direction of said carrier.
- 20 25. 17. A rotary sheet carrier having an abutment thereon, a sheet front gage adapted to position a sheet relatively to said carrier and a wiper constructed and arranged to coöperate with said abutment to move a sheet toward said gage.
- 25 30. 18. A rotary sheet carrier, a sheet front gage mounted thereon, a sheet wiper adjacent said carrier and a wiper abutment on said carrier, constructed and arranged to coöperate with said wiper to move a sheet toward said gage.
- 30 35. 19. A sheet carrier, a sheet front gage movably mounted thereon, a sheet wiper adjacent said carrier, a wiper abutment on said carrier, constructed and arranged to coöperate with said wiper to move a sheet toward said gage and means to move said gage toward the sheet while it is engaged by said wiper.
- 35 40. 20. A sheet carrier, a sheet front gage movably mounted thereon, a sheet wiper adjacent said carrier, a wiper abutment on said carrier, constructed and arranged to coöperate with said wiper to move a sheet toward said gage, means to move said gage toward the sheet while it is engaged by said wiper, and means to regulate the amount of motion of said gage.
- 40 45. 21. A sheet carrier, a sheet front gage movably mounted thereon, a sheet wiper adjacent said carrier, a wiper abutment on said carrier, constructed and arranged to coöperate with said wiper to move a sheet toward said gage, means to move said gage toward
- the sheet while it is engaged by said wiper, means to regulate the amount of motion of said gage and operable while said carrier is in motion.
- 45 50. 22. A sheet carrier having a gripper finger shaft thereon and sheet grippers on said shaft, means to rotate said shaft to close said grippers at a predetermined point of travel of said carrier, gripper abutments on said carrier arranged to coöperate with said sheet grippers, a sheet guide loosely mounted on said shaft, connections between said shaft and said guide constructed and arranged to cause the rotation of said shaft to move said guide into sheet guiding position above said abutments and a stop to determine the operative position of said sheet guide, said connections being constructed and arranged to permit the further rotation of said shaft after said guide has reached its operative position.
- 50 55. 23. A sheet carrier, sheet gripping means and movable sheet guiding means on said carrier and a single means to bring first the sheet guiding means and then the sheet gripping means into operative position, said guiding means and said gripping means operating on the same side of the sheet.
- 55 60. 24. A sheet carrier, sheet guiding and gripping devices thereon and a single means to move said devices to first guide the edge of a sheet to said carrier and then engage the sheet with said carrier, said guiding means and said gripping means operating on the same side of the sheet.
- 60 65. 25. A sheet carrier having sheet grippers and gripper abutments thereon, a sheet overguide movably mounted on said carrier and a single means to bring said guide into operative position and to close said grippers on said abutments, said guiding means and said gripping means operating on the same side of the sheet.
- 65 70. 26. A sheet carrier having a shaft, sheet grippers attached to said shaft, gripper abutments on said carrier, a sheet overguide mounted on said shaft and yieldingly connected thereto, and means to rotate said shaft to bring said grippers into contact with said abutments and said overguide into operative position.
- 70 75. 27. A sheet carrier having sheet grippers and gripper abutments thereon, a sheet gage on said carrier and a sheet guide on said carrier, independent of said gage and positioned relatively to said abutments to form a pathway therewith to guide the edge of a sheet to said gage.
- 75 80. 28. A sheet carrier having sheet grippers and gripper abutments thereon, a sheet gage on said carrier and a sheet guide on said carrier, independent of said gage and arranged to project over said gage and in contact with the top thereof.
- 80 85. 29. A sheet carrier, a member on said car-

rier, a sheet gage on said carrier, adjacent said member and projecting above the surface thereof, and a sheet guide on said carrier, independent of said gage and arranged 5 to project over said member and above the surface thereof.

30. A sheet carrier, a member on said carrier, a sheet gage on said carrier, adjacent said member and projecting above the surface thereof, and a sheet guide on said carrier, independent of said gage and arranged 10 to project over said member and above the surface thereof in contact with the top of said gage.

31. A sheet carrier, a member on said carrier, a sheet gage on said carrier, adjacent said member and projecting above the surface thereof, and a sheet guide on said carrier, independent of said gage and arranged 20 to project over said member and above the surface thereof in contact with the top of said gage, the top of said gage being adjustably held above the surface of said member.

32. A sheet carrier, a member on said carrier, a sheet gage on said carrier, adjacent said member and projecting above the surface thereof, a pair of sheet guides on said carrier, spaced apart and arranged to extend over the surface of said member and removed therefrom and means operating 30 between said guides to move a sheet toward said gage.

33. A sheet carrier, a member on said carrier, a sheet gage on said carrier, adjacent said member and projecting above the surface thereof, a pair of sheet guides on said carrier, spaced apart and arranged to extend over the surface of said member and 40 removed therefrom and a sheet wiper operating between said guides to move a sheet toward said gage.

34. A sheet carrier having sheet grippers and gripper abutments thereon, a sheet 45 gage on said carrier, a movably mounted sheet guide on said carrier and independent of said gage, and means to move said guide into position to guide the edge of a sheet against said gage.

35. A sheet carrier having sheet grippers and gripper abutments thereon, a sheet gage on said carrier, independent of said gage and a movably mounted sheet overguide on said carrier, arranged to project over said 55 abutments and above the plane thereof, and means to move said guide into and out of operative position.

36. A carrier, sheet grippers and gripper abutments thereon, a sheet gage on said carrier, a sheet overguide on said carrier, independent of said gage, and means to move 60 a sheet against said gage and between said abutments and said overguide.

37. A carrier, sheet grippers and gripper abutments thereon, a sheet gage on said car-

rier, a sheet guide on said carrier, movable with respect to said gage and extending over said gage and resting on the top thereof and means to move a sheet against said gage and between said abutments and said 70 guide.

38. A carrier, sheet grippers and gripper abutments thereon, a sheet gage on said carrier, a sheet overguide on said carrier, a sheet wiper adjacent the closing point of 75 said grippers and a wiper abutment on said carrier arranged to coöperate with said wiper to move a sheet against said gage and between said abutments and said guide.

39. A carrier, sheet grippers and gripper 80 abutments thereon, a movably mounted sheet gage on said carrier, a sheet overguide on said carrier, independent of such gage, means to move a sheet against said gage and between said abutments and said guide and 85 means to move said gage against said sheet.

40. A carrier, sheet grippers and gripper abutments thereon, a movably mounted sheet gage on said carrier, a sheet overguide on said carrier, independent of said gage and 90 extending over said gage and resting on the top thereof, means to move a sheet against said gage and between said abutments and said guide and means to move said gage against said sheet while said guide is resting on said gage.

41. A sheet carrier having a shaft, sheet grippers on said shaft, gripper abutments on said carrier, sheet guides on said shaft and yieldingly connected thereto, means to rotate said shaft to close said grippers at the feeding point of said carrier and to bring said guides into yielding position over said abutments and removed therefrom, a sheet support adjacent said feeding point, a rotating member arranged to engage a sheet on said support and move it toward said gage and means to move said gage toward said sheet while said carrier is in motion.

42. A sheet carrier, a plurality of movably mounted sheet front gages thereon, means to move each of said gages in a direction the reverse of that of said carrier and while said carrier is in motion and means to control the amount of motion of each of said 110 gages independently of the amount of motion of any of the other gages.

43. A sheet carrier, a plurality of movably mounted sheet front gages thereon, means to move each of said gages in a direction the reverse of that of said carrier and while said carrier is in motion and means, operable while said carrier is in motion, to control the amount of motion of each of said gages independently of the 120 amount of motion of any of the other gages.

44. A sheet carrier, a plurality of movably mounted sheet front gages thereon, means to move each of said gages in a direction the reverse of that of said carrier 125

130

and while said carrier is in motion, means to control the amount of motion of each of said gages independently of the amount of motion of any of the other gages, and 5 means to move a sheet toward said gages at a speed greater than that of said carrier.

45. A pair of adjustable sheet front gages, adjusting means for each of said gages for shifting the gaging position thereof, a manually operable member remote from said gages and motion transmitting connections between said member and said operating means, said connections being adapted and arranged to transmit motion to one or to 15 both of said adjusting means at the will of the operator.

46. A pair of adjustable sheet front gages, adjusting means for each of said gages for shifting the gaging position thereof, a pair 20 of manually operable members remote from said gages, a set of motion transmitting connections between one of said members and one of said adjusting means, a set of motion transmitting connections between the 25 other of said members and the other of said adjusting means, and disconnectible means arranged to transmit motion from one of said sets to the other.

47. A pair of adjustable sheet front gages, 30 adjusting means for each of said gages for shifting the gaging position thereof, manually operable means remote from said gages, and motion transmitting connections between said manually operable means and said adjusting means, said connections being constructed and arranged to enable the shifting of either of said gages individually or both of said gages simultaneously, at the will of the operator, when said manually operable means are moved.

48. In a printing press, the combination with the impression cylinder, and its grippers, of means for imparting front register to a sheet fed to the cylinder comprising a 45 gage-support moving forwardly with the sheet, a gage adjustably connected to the support, and stationary means to vary the adjustment of said connection whereby to adjust the position of the gage while the press is in motion.

49. The combination of a sheet carrier having sheet grippers thereon, of means for imparting front register to a sheet fed to said carrier, comprising a front gage, means 55 to support and move said gage forwardly with the sheet, and stationary means to move said support to vary the gaging position of said gage while it is in motion, and means to maintain the edge of the sheet against said gage while said grippers close thereon.

50. In combination, a sheet carrier having sheet grippers thereon and means to vary the front margin of sheets fed to said carrier comprising a sheet front gage, means

to support and move said gage toward said carrier, and stationary means operable while said gage and said grippers are in motion to shift the position of said gage on said supporting and moving means to vary the operative relation between said grippers and 65 said gage.

51. In combination, a sheet gripper, means for supporting and moving said gripper, a sheet front gage, means for supporting and moving said gage with said gripper, and stationary means operable while said gage and said gripper are in motion, to vary the 75 gaging position of said gage with relation to said gripper.

52. In combination, a sheet carrier having a sheet gripper thereon, means for opening and closing said gripper, a front gage on said carrier and stationary means, operable while said carrier is in motion, to shift the gaging position of said gage with relation 85 to said carrier.

53. A sheet carrier, sheet grippers thereon, a moving sheet gage constructed and arranged to coöperate with said sheet gripper, and means, operable while said sheet gage is 90 in motion, to vary the gaging position of said gage with relation to the closing point of said grippers to vary the front margin of the sheet.

54. A sheet carrier, sheet grippers thereon, a pair of moving sheet gages adapted to coöperate with said sheet grippers, and means, operable while said sheet gages are in motion, to vary independently the gaging position of each of said sheet gages with relation to the closing point of said grippers, 100 to vary the front margin of the sheet.

55. A sheet carrier, sheet grippers thereon, means to support and move a sheet front gage forwardly with a sheet being fed to 105 said carrier and stationary means operable while said gage is in motion, to vary the gaging position of said gage, and thereby to vary the front margin of the sheet when it is taken by said sheet grippers.

56. In combination, a sheet gripper, means for supporting and moving said gripper, means to close said gripper at a predetermined point in its path, means to move a sheet toward the closing point of the gripper, a sheet front gage, means for supporting and moving said gage with the sheet, means to engage the sheet frictionally and move it up to said gage, and stationary means, operable while said gage is in motion, 120 to vary the gaging position of the gage.

57. In combination, a sheet gripper, means for supporting and moving said gripper, means to close said gripper at a predetermined point in its path, means to move a sheet toward the closing point of the gripper, a sheet front gage, means for supporting and moving said gage with the sheet, and

means, operable from a fixed point, to vary the gaging position of the gage while it is in motion.

58. A cylinder having sheet grippers thereon, means to forward a sheet toward the closing point of said grippers, a sheet gage, means to support and rotate said gage constructed and arranged to move the gage with the sheet during a portion of the travel 10 of the gage, and means, operable from a fixed point, to vary the gaging position of the gage while it is in motion.

59. A cylinder having sheet grippers thereon, means to forward a sheet toward the closing point of said grippers, a rotary member adjacent the path of the sheet, a gage on said member adapted to gage the sheet while the sheet and the gage are in motion, and means, operable from a fixed 15 point, to vary the gaging position of the gage while it is in motion.

60. The combination of a sheet carrier

having sheet grippers thereon, of means for imparting front register to a sheet fed to 25 said carrier, comprising a front gage, means to support and move said gage forwardly with the sheet, means, operable from a fixed point, to vary the gaging position of said gage while it is in motion, and means to 30 maintain the edge of the sheet against said gage while said grippers close thereon.

61. A sheet carrier, a sheet front gage movably mounted thereon, means to move said gage into gaging position while said 35 carrier is in motion and means to alter said gaging position while said carrier is in motion.

62. A sheet carrier, a sheet front gage movably mounted thereon, means to move 40 said gage into gaging position while said carrier is in motion and means controlled from a point remote from said gage, to alter said gaging position while said carrier is in motion.

45 63. A sheet carrier, a sheet front gage movably mounted thereon, means to move said gage in a direction the reverse of that of said carrier and while said carrier is in

motion and means, operable while said carrier is in motion, to control the amount of 50 motion of said gage.

64. A sheet carrier, a sheet gage movably mounted thereon and means to shift the gaging position of said gage while said carrier is in motion.

55 65. A sheet carrier, a sheet gage movably mounted thereon and means controlled from a point remote from said gage to shift the gaging position of said gage while said carrier is in motion.

60 66. A sheet carrier, a movably mounted sheet gage, means controlled from a point remote from said gage, to alter the gaging position thereof and an index to indicate the position of said gage.

65 67. A sheet carrier, a sheet gage movably mounted thereon, means controlled from a point remote from said gage, to alter the gaging position thereof and an index to indicate the position of said gage.

70 68. A sheet carrier, a sheet gage movably mounted thereon and means to shift the gaging position of said gage while said carrier is in motion, to increase or decrease the margin of a sheet presented to said carrier.

75 69. A sheet carrier, a sheet gage movably mounted thereon and means controlled from a point remote from said gage, to shift the gaging position of said gage while said carrier is in motion, to increase or decrease the margin of a sheet presented to said carrier.

80 70. A rotatable cylinder, an arm having a sheet gage thereon and loosely mounted on said cylinder, mechanism between said arm and a portion of said cylinder and 85 constructed and arranged to move said arm relatively to said cylinder, a cam, independent of said cylinder, constructed and arranged to cooperate with said mechanism to shift said gage as said cylinder rotates 90 and means to shift said cam to control the shifting of said gage.

JOSEPH WHITE.

JOHN W. DAUB.

Corrections in Letters Patent No. 1,367,110.

It is hereby certified that in Letters Patent No. 1,367,110, granted February 1, 1921, upon the application of Joseph White, of Piscataway township, New Jersey, for an improvement in "Sheet Registering and Gaging Mechanism," errors appear in the printed specification requiring correction as follows: Page 7, lines 52-53, claim 35, strike out the words "independent of said gage and"; same page and claim, line 54, after the word "carrier" insert the words *independent of said gage and*; and that the said Letters Patent should be read with these corrections therein that the same may conform to the record of the case in the Patent Office.

Signed and sealed this 1st day of March, A. D., 1921.

[SEAL.]

L. B. MANN,

Acting Commissioner of Patents

Cl. 271—53.
